US0D1062076S

(12) **United States Design Patent** (10) **Patent No.:** **US D1,062,076 S**
(45) **Date of Patent:** **** Feb. 11, 2025**

(54) **PROTECTIVE HELMET**

(71) Applicant: **TECMEN ELECTRONICS CO., LTD**, Jiangsu (CN)

(72) Inventor: **Ziqian Wu**, Nanjing (CN)

(73) Assignee: **TECMEN ELECTRONICS CO., LTD**, Nanjing (CN)

(**) Term: **15 Years**

(21) Appl. No.: **29/823,756**

(22) Filed: **Jan. 19, 2022**

(30) **Foreign Application Priority Data**

Jul. 19, 2021 (CN) 202130456576

(51) **LOC (15) Cl.** **02-03**

(52) **U.S. Cl.**

USPC **D29/107**

(58) **Field of Classification Search**

USPC D29/100, 102, 104, 105, 106, 107, 108, D29/110, 122; D24/110.1, 110.3

(57) **CLAIM**

The ornamental design for a protective helmet, as shown and described.

DESCRIPTION

FIG. 1 is a front perspective view of a protective helmet showing my new design;

FIG. 2 is a front elevation view of the protective helmet of FIG. 1;

FIG. 3 is a rear elevation view of the protective helmet of FIG. 1;

FIG. 4 is a right side view of the protective helmet of FIG. 1;

FIG. 5 is a left side view of the protective helmet of FIG. 1; FIG. 6 is a top view of the protective helmet of FIG. 1; and, FIG. 7 is a bottom view of the protective helmet of FIG. 1. The broken lines shown in the drawings represent portions of the protective helmet that form no part of the claimed design.

1 Claim, 7 Drawing Sheets
